UNITED STATES PATENT OFFICE.

MILDRED C. SCHMOLZE, OF NEW YORK, N. Y., ASSIGNOR TO FRANKLIN SIMON & COMPANY, INC., OF NEW YORK, N. Y., A CORPORATION OF NEW YORK.

DESIGN FOR A DRESS.

Application filed September 19, 1928. Serial No. 28,211. Term of patent 3½ years.

To all whom it may concern:

Be it known that I, MILDRED C. SCHMOLZE, a citizen of the United States, and a resident of the city of New York, (borough of Manhattan) in the county of New York, and State of New York, have invented the new, original, and ornamental Design for Dress, of which the following is a specification.

The characteristic features of the garment include the arrangement which shows a folded ornamental member sometimes known as a jabot depending from the neck opening of the dress, another ornamental member depending from the tucked portion and substantially in line with the jabot and a third depending portion at the bottom of the skirt conforming substantially to the appearance of the jabot.

Reference is had to the accompanying drawing, forming part thereof, wherein

Figure 1 is a three-fourths front perspective view of a dress showing my new design, the same being illustrated on a figure indicated by dotted lines;

Figure 2 is a rear view of the dress shown in Figure 1, the same being illustrated on a figure indicated by dotted lines.

I claim:

The ornamental design for a dress substantially as shown and described.

Signed at New York, in the county of New York and State of New York this 17 day of September, A. D. 1928.

MILDRED C. SCHMOLZE.
